UNITED STATES PATENT OFFICE

2,004,557

DIRECTION INDICATOR

John L. Trotter and Virgil Hall, St. Louis, Mo.

Application May 26, 1931, Serial No. 540,116

3 Claims. (Cl. 116—42)

This invention has reference to signals designed for use on motor vehicles, and aims to provide means operable from a point within the vehicle for indicating to approaching motorists, the direction of travel to be taken by the vehicle equipped with the device.

An important object of the invention is to provide a signal of this character including a movable indicator which may be moved to various angles to permit the use of the spotlight, forming a part of the signal, with facility.

A further object of the invention is to provide a signaling member, and a movable arm mounted within the signaling member, means being provided for oscillating the arm, to attract the attention of motorists driving near the vehicle.

A still further object of the invention is to provide controlling means mounted on the steering wheel of the vehicle, thereby permitting the operation of the signal to control the signal, without the necessity of the operator removing his hands from the steering wheel.

With the foregoing and other objects in view, which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

Referring to the drawings:

Figure 1 is an elevational view of a direction indicator, constructed in accordance with the invention.

Figure 2 is a longitudinal sectional view through the indicator housing.

Figure 3 is a diagram illustrating the circuits leading to the motor and various lights of the indicator.

Figure 4 is a vertical sectional view through the indicator supporting arm and indicator housing.

Figure 5 is a transverse sectional view taken on line 5—5 of Figure 1.

Referring to the drawings in detail, the device comprises a hollow support 5 which is provided with a reduced portion 6 of a length to extend through the side of the vehicle body, which in the present showing is indicated by the reference letter A.

Securing members 7 are provided on the reduced portion, and act to secure the support 5 in position. The support 5 is substantially wide at its outer end, and is provided with a cut out por-

tion to accommodate the circular flange 8 depending from the base of the signal supporting post 9 that is provided with a bearing 10 near its upper end, to support the shaft 11 of the housing 12, the shaft 11 being rotatably mounted within the bearing 10. Coiled springs 13 and 14 respectively connect with opposite sides of the vertical supporting post, near the base thereof, the opposite ends of the springs being secured to the inner end of the support 5, by means of the plates 15. These springs 13 and 14 are normally under tension, so that when the supporting post 9 is rotated about a vertical axis, these springs will act to return the supporting post 9 to its normal position.

Secured to the shaft 11 is a collar 16 to the upper side of which is secured a coiled spring 17, the spring being anchored within the post 9. A coiled spring 18 connects with the collar 16 at the lower side thereof, the opposite end of the spring 18 being secured within the post. Thus it will be seen that due to this construction, the shaft 11, is held in balance, and that when it is rotated, to change the angle of the housing 12, the shaft will return to its normal position, when the knob 19, by means of which the shaft and housing are rotated, is released.

Secured to one side of the housing 12, is a spotlight 20 which extends forwardly from the housing, the lamp of the spotlight being supplied with electric energy from a suitable source of supply, through the wire 21, the circuit to the lamp being controlled by means of the switch 22 which is supported on the knob 19 to be engaged by the thumb or finger of the operator, so that when it is desired to move the housing to operate the spotlight, the lamp may be lighted. This housing 12 has its rear surface closed by means of the wire mesh material 23, so that the indicating arm 24 will be invisible in the daylight, unless the lamp, to be hereinafter more fully described, is lighted. Pivotedly mounted on the shaft 24, supported within the housing, is an indicating arm 24, which arm is hollow and has its rear surface formed with cut out portions defining letters indicating the word "left". A lamp 25 is mounted within the indicating arm 24 and projects light rays through the letters so that the letters will be clearly outlined. The outer end of the indicating arm 24 is closed by glass, so that light rays may be projected towards the curved end 26 of the housing 12. Formed at the inner end of the indicating arm 24 is a finger 27 against which the spring 28 engages, the spring being mounted on the lug 29, so that when the finger moves downwardly,

the spring 28 will be compressed to return the arm to its active position.

Mounted on the housing 12 is a motor 30 which includes an oscillating shaft on which the arm 31 is mounted, the arm 31 being of a length to contact with the finger 27 as it operates, causing the indicating arm 24 to swing vertically to attract the attention of persons passing near the vehicle equipped with the device.

10 Electric current is supplied to the lamp 25 through the wires 32 which extend through the shaft 11, post 9 and support 5, where they connect with the switch 33 mounted on the steering wheel 34 of the vehicle, so that the operator may 15 by operating the switch, control the light within the arm 24.

As clearly shown by Figure 4 of the drawings, the support 5 is provided with a depressed portion 35 defining a housing for the trouble lamp 36 which is formed with threads 37, to cooperate with threads formed in the bottom of the depressed portion 35. The wire leading from the source of electricity supply to the lamp 36, is indicated by the reference character 38 and is coiled around the base of the depressed portion and held in position by means of the removable cup shaped member 39 which is held in position by means of the set screws 40.

The reference character 41 designates a mirror 30 that is mounted on the arm 42, that extends through the bracket 43, so that the mirror may be adjusted vertically for the convenience of the operator. A switch 44 controls the circuit to the trouble lamp 36 and may be disposed in any suitable place near the operator, so that the operator may have easy access thereto.

From the foregoing it will be obvious that due to the construction shown and described, the operator of the vehicle may by pressing the switch 40 33 complete the circuit to the lamp 25, illuminating the indicating arm 24, indicating to people approaching from the rear, that the vehicle

equipped with the indicator, is to make a left hand turn.

It will of course be understood that the switch 33 also controls the current to the motor 30, so that simultaneously with the operation of the motor, the lamp 25 will be lighted. Should it be desired to use the spotlight, the housing may be readily tilted in a manner as described, to properly direct the light rays from the spotlight

20.

We claim:

1. In a device of the class described, a hollow support, a vertical supporting post, a circular flange at the lower end of the supporting post and fitted in the hollow support, holding the supporting post in an upright position, spring members connected to the opposite sides of the supporting post and adapted to hold the supporting post in a predetermined position, a signaling housing mounted at the upper end of the post, and signaling means within the signaling housing.

2. In a device of the class described, a supporting post, a signal housing mounted for rotary movement at the upper end of the supporting post, a wall closing the front end of the signal housing, a wall of wire mesh material closing the rear side of the signal housing, a movable signal arm within the signal housing and means for illuminating the signal arm.

3. In a signaling device of the class described, a supporting post, a signal housing mounted at the upper end of the supporting post, a signaling arm pivotally mounted within the signal housing, an arm within the signal housing and engaging one end of the signaling arm for swinging the signaling arm in one direction, a coiled spring engaging the signaling arm for moving the signaling arm in the opposite direction, and means for illuminating the signaling arm.

JOHN L. TROTTER.

VIRGIL HALL.
